AUTOMOBILE DOOR GUARD

Erick H. Bjorum, 640 Island View Drive, Seal Beach, Calif. 90740; John G. Gibson, 18985 Santa Nadrina Circle, Fountain Valley, Calif. 92708; and Morgan C. Lindberg, 12840 Riverside Drive, North Hollywood, Calif. 91607

Filed Nov. 5, 1969, Ser. No. 19,960

Term of patent 14 years

Int. Cl. D12—14

U.S. Cl. D14—6

FIG. 1 is a front perspective view of an automobile door guard showing our new design;

FIG. 2 is a top plan view of said door guard;

FIG. 3 is a side elevational view thereof, with the side opposite FIG. 3 having the same appearance as that of FIG. 3;

FIG. 4 is a front elevational view of said door guard;

FIG. 5 is a rear elevational view of said door guard; and

FIG. 6 is a bottom view thereof.

We claim:

The ornamental design for an automobile door guard, substantially as shown and described.
